(57) **CLAIM**

The ornamental design for a film cartridge packaging container, as shown and described.

DESCRIPTION

FIG. 1 is a top, front and side perspective view of a film cartridge packaging container showing our new design; FIG. 2 is a front elevational view thereof; FIG. 3 is a rear elevational view thereof; FIG. 4 is a top plan view thereof; FIG. 5 is a bottom plan view thereof; FIG. 6 is a side elevational view thereof taken from the right of FIG. 2, the side elevational view from the left of FIG. 2 being the mirror image thereof; and, FIG. 7 is a plan view thereof in an unfolded state.
